(57) **CLAIM**

I claim the ornamental design for a rear view mirror, as shown and described.

DESCRIPTION

FIG. 1 is a Perspective view of a rear view mirror showing my new design;

FIG. 2 is a Front view thereof;

FIG. 3 is a Back view thereof;

FIG. 4 is a Right-side view thereof;

FIG. 5 is a Left-side view thereof;

FIG. 6 is a Top view thereof;

FIG. 7 is a Bottom view thereof; and,

FIG. 8 is an exposed top view thereof.

The broken lines in the drawings depict portions of the rear view mirror that form no part of the claimed design.

1 Claim, 6 Drawing Sheets
